(57) **CLAIM**

The ornamental design of a carton holder, as shown and described.

DESCRIPTION

My design relates to a holder for holding beverage cartons of the like used for containing milk and juice. The carton holder is designed to sit on a flat surface and be lifted by a single hand.

FIG. 1 is a perspective front view of my new design. The hashed lines delineate a carton and are not part of my claimed design.

FIG. 2 is a top view thereof.

FIG. 3 is a bottom view thereof.

FIG. 4 is a back elevation view thereof. The hashed lines delineate a carton and are not part of my claimed design.

FIG. 5 is a front elevation view thereof. The hashed lines delineate a carton and are not part of my claimed design; and,

FIG. 6 is a side elevation view thereof. The hashed lines delineate a carton and are not part of my claimed design.
